UNITED STATES PATENT OFFICE.

JOHN FREEMAN, OF NEW YORK, N. Y., ASSIGNOR TO SAVE-A-ROOM FURNITURE MANUFACTURING COMPANY, INC., OF NEW YORK, N. Y., A CORPORATION OF DELAWARE.

COUCH-BED.

1,381,292.

Specification of Letters Patent. Patented June 14, 1921.

Application filed May 14, 1919. Serial No. 297,056.

To all whom it may concern:

Be it known that I, JOHN FREEMAN, a citizen of the United States, residing at 2 East 181st street, New York city, in the 5 county of Bronx, State of New York, have invented certain new and useful Improvements in Couch-Beds; and I do hereby declare the following to be a full, clear, and exact description of the invention, such as 10 will enable others skilled in the art to which it appertains to make and use the same.

The present invention relates to couch beds, and particularly to those of simple 15 and effective construction, readily and easily convertible from day couches to night beds, and vice versa.

Heretofore it was customary to unfold the body of the couch, either lengthwise or transversely. While these arrangements provided for converting a chair to a bed of 20 greater length, or a couch to a bed of greater width, the construction is comparatively expensive in its mechanical features and upholstery, and the change involves considerable 25 physical effort. Furthermore, the construction does not lend itself well to such comfortable and sightly furniture in both uses, and is usually not well adapted for sanitary storage of the bedding within.

30 In accordance with one part of my invention, the couch bed has a base and a reversible body adapted to be seated on the base with either of its sides, that is, the couch side or bed side, uppermost. Between the 35 base and the body is a moving fulcrum, preferably consisting of supporting members carried by the body at its respective ends. The base and body are joined by a vertically-movable pivot connection or connections, 40 preferably consisting of pivots carried by the body at its respective ends and a plurality of links connected to each of the pivots and the base. The reversal of the body on the base may be performed by the operator with 45 a minimum of physical effort and without noise or shock by reason of the inclusion in the couch bed of an instrumentality for assisting in the elevation of the vertically-movable pivot connection during the movement of the fulcrum in one direction and 50 opposing the fall of the vertically-movable pivot connection during the movement of the fulcrum in the other direction as the body is turned for reversing. This instru-

mentality may consist of a spring or springs, 55 preferably connected between the base and the links.

Irrespective of the moving fulcrum between the base and body, and whether or not the pivot connection between the base and 60 body is vertically movable, the reversible body may carry pivots at its respective ends and the couch bed may have a plurality of links connected to each of the pivots and the base, and springs connected between the base 65 and the links so as to tend to raise the body from the base and oppose its fall to the base as the body is turned on its pivots for reversing. The springs are preferably connected to the base by spring tensioning 70 means for adjusting the stress of the springs to provide for different weights of bedding and to adjust the effort required in reversing the body.

In the specific embodiment described 75 hereinafter the mechanism at the two ends of the base and reversible body includes links which are journaled on pivot pins extending centrally from the ends of the body and pivoted to bell crank levers which in 80 turn are pivoted to the base. The springs connect the ends of the bell crank levers through tensioning means with the base and are under stress when the body is seated on the base with either side uppermost, so that 85 the springs assist in raising the body and partly counterbalance the body in falling. Also, the ends of the body have supporting members with rounded ends, which roll and slide to and from a seated position on the 90 base, thereby further easing the converting operation and rendering the structure more durable and secure by providing a moving fulcrum between the body and base.

The invention further comprehends as 95 another of its parts a reversible couch bed having a base, a reversible body adapted to be seated on the base with either side uppermost and connecting means pivoted to the base and to the end walls of the body. The 100 pivotal points of the body may be vertically shiftable into an elevated position on the raising of the body while parts of the opposite ends of the body are always in engagement with and guided by the base during 105 the raising movement of the body preparatory to the reversal thereof. In order to insure the proper seating of the body on the

base after reversal, under the severest conditions of usage, the connecting means is constructed and arranged to limit the vertical movement of the pivotal points of the body during the reversal thereof. Moreover, the pivotal points of the body may, by reason of the construction and arrangement of the connecting means, be displaced laterally of the base either forwardly or rearwardly, when the body is disposed at an angle to, and parts of its opposite ends are in engagement with the base, to render any part of the interior of the base accessible from above for the removal of the bedding or other articles stored therein. Notwithstanding, lateral movement of the pivotal points is precluded by the connecting means when the body is seated on the base so that displacement of the body when in use with either side uppermost cannot occur. The connecting means may comprise a pair of links, preferably two pairs of similarly formed links, one pair at each side of the median line of the base, the pivotal connection of the link, or one link of each pair with the base, being closer to the median line of the base at all times than is the pivotal connection between the links. Furthermore, means may be included in this construction which is effective to assist in the elevating of the pivotal connecting means in a vertical direction thereby to assist in the raising of the body from the base and opposing its fall thereto. Such means may consist of a spring connected to the link that is pivotally connected to the base, or a pair of oppositely acting springs one connected to each link that is pivotally connected to the base.

Whether or not the mechanism includes means for assisting in the raising of the body from the base and opposing its fall thereto, but preferably including a pair of oppositely acting springs, one connected to each link that is pivotally connected to the base, the reversible body may be adapted to be seated on the base with either side uppermost and is reversible by drawing it upwardly first to an inclined position and then to a perpendicular position. The pivotal points of the body are elevated upon raising the body into an inclined position and further elevated upon raising the body into a perpendicular position and lowered upon lowering the body, the connecting means being constructed and arranged to limit the vertical movement of the pivotal points of the body during its reversing movement. In this construction the connecting means may comprise a pair of links, preferably two pairs of similarly formed links, one at each end of the median line of the base, the pivotal connection of the links, or of one of each pair, with the base being closer to the median line of the base at all times than is the pivotal connection between the links. In the speci-

fic embodiment described hereinafter the pivotal points of the body are in alinement with the median line of the base.

Whether the couch bed is made in accordance with one or the other of the parts of my invention as described in the foregoing, one side of the body may be upholstered in conformity with the outside parts of the couch bed so as to form an attractive piece of furniture for day use, whereas, the other side is covered like a mattress and may have the bedding attached to it, the springs serving both sides, and the base supporting the reversible body in either position.

Inasmuch as the body does not move longitudinally in its reversing movement, the heads may be fixed to the frame, and since the body may revolve about a median line on the pivot pins, the couch bed may have a fixed back like a davenport.

In the accompanying drawings, illustrating the preferred form of construction in which, as an example, raising and lowering heads are combined with the reversible body in a couch bed without a back,

Figure 1 is a perspective view of the upholstered structure showing the operating mechanism; Fig. 2 is a transverse section, particularly showing the couch springs; Fig. 3 is an end elevation of Fig. 1; Fig. 4 is a front view of the base with the body in raised position; Fig. 5 is an end view of the reversing mechanism; Fig. 6 is an enlarged detail of the pawl and ratchet mechanism for the heads; Fig. 7 is a front view thereof; and Fig. 8 is a perspective view of the device as a day couch.

The base of the couch bed consists of an open rectangular frame of wood having longitudinal stringers 1, crosspieces 2, cross braces 3, and feet 4, one or both stringers being apertured for ventilation as at 5.

The body consists of an open rectangular frame of wood comprising the longitudinal stringers 6 and crosspieces 7 and braces 8, the body being of less length than the base but of substantially the same width. Fastened on each crosspiece 7 is a supporting member 9 having rounded ends at 10 adapted to roll and slide on the crosspieces 2 as the body is moved from and to its seated position on the base, thereby forming between the base and body moving fulcrums which slide forwardly as the body rises and rearwardly as the body falls. The interconnected mattress springs 11 are fastened to the body in any suitable way and form the cushion for both the top and bottom thereof.

The pivot pins 12 extend through the supporting members 9 about centrally of the ends of the body. The links 13 are journaled on the pivot pins and are pivotally connected at their other ends to the bell crank levers 14 which are pivoted at 15 to the cross pieces 2 of the base. The springs 130

16 are connected between the other ends of the bell crank levers and the threaded tensioning rods 17, which pass through the angle irons 18 on the base and are provided 5 with nuts 19 for adjusting the normal tension of those springs.

Whether the couch side 20, or the bed side 21, is uppermost, the body is seated on the base by the supporting members 9 resting on 10 the crosspieces 2 of the base. In this normal position, the link mechanism at each end of the couch body is collapsed, and the springs 16 are under stress on account of their extension, as shown best in Fig. 3. To 15 reverse the body on the frame, the body is raised by hand. The link mechanism at the two ends guides the pivot pins 12 in a vertical direction without longitudinal displacement relatively to the base, and partially 20 supports the body as it rises and falls. The springs 16 assist in raising the body by passing from a stressed condition when the body is seated, to an unstressed condition when the body is at its raised position. As the 25 body is being raised to its uppermost position, as shown best in Fig. 5, it is turned by the operator in either direction of rotation to bring the other side to the top, the body being turned easily about its median line 30 passing through its centrally arranged pivot pins 12. As the body falls the link mechanism collapses and the springs 16 check the fall in becoming extended. As a result of those springs, and the combined rolling and 35 sliding motion of the rounded ends of the supporting members on the crosspieces, the body seats itself securely without appreciable noise or shock. It will be observed that the vertical movement of the pivot 40 points 12 is limited by the link mechanism to insure the proper seating of the body even though operated so vigorously in reversing as to cause the supporting members 9 to become disengaged from the crosspieces 2.

45 Under such conditions, the link mechanism operates to arrest the vertical movement of the body and to constrain the reversal of the body about its median line and its proper seating after reengagement of the 50 supporting members 9 with the crosspieces 2 under the action of gravity.

The couch has two heads consisting of the curved arms 22 and the cross members 23. Each head is pivotally connected to the base 55 by hinges 24, and the stringers are provided with notches at 25 to accommodate the heads in various positions. At each end of the couch, there is a ratchet 26 fastened to the base. Each head carries a pawl 27 pivotally 60 connected to it and carrying a connecting chain 28 extending to a handle 29 outside the upholstery on the head. The yoke 30 is pivoted to the ratchet and closely embraces the pawl 27, the arrangement being such 65 that the yoke forces the pawl into the upper-

most tooth of the ratchet when the head falls to its lowermost position. The pin 31 on the ratchet prevents the pawl from falling too low when the head is fully raised. As a result of the fact that the yoke closely embraces the pawl, substantial lateral movement thereof is prevented, so that both the pawl and the ratchet may be made of comparatively thin metal without likelihood of lateral disengagement. 75

Either head may be raised or lowered after disengaging its pawl from the ratchet, the body preventing the head from moving inwardly beyond a predetermined position, and the yokes 30 preventing the heads from 80 falling below a predetermined position.

The upper side of the body is upholstered in conformity with the remaining parts of the couch bed, whereas the under side of the bed is covered with ticking and may 85 carry the bedding which, when the couch bed is made up as a couch, occupies the ventilated space within the base. It will be observed from Fig. 8 that the upholstery permits the unimpeded raising and lowering 90 movements of the heads, and provides for a finished appearance to the couch by having the upholstery of the heads extend slightly over the upholstery of the body. In this construction, the heads should be 95 lowered to a convenient sleeping position before the body is raised for reversal.

The mechanism for raising and lowering the heads of the couch forms the subject matter of a divisional application, Serial 100 No. 318,483, filed August 19, 1919.

Having thus described my invention, what I claim is:

1. In a couch bed, a base, a reversible body adapted to be seated on the base with either side uppermost, double-ended supporting members carried by the body at its respective ends to form moving fulcrums and vertically-movable pivot connections between the base and the body, and springs assisting in the elevation of the vertically-movable pivot connections during the movement of the fulcrums in one direction and opposing the fall of the vertically-movable pivot connections during the movement of the fulcrums in the other direction as the body is turned for reversing. 105 110

2. In a couch bed, a base, a reversible body adapted to be seated on the base with either side uppermost, supporting members carried by the body at its respective ends and having rounded ends to roll and slide on the base, vertically-movable pivot connections between the base and the body, and springs assisting in the elevation of the vertically-movable pivot connections during the rolling and sliding movement of said rounded ends in one direction and opposing the fall of the vertically-movable pivot connections during the rolling and sliding 120 125 130

movement of said rounded ends in the other direction as the body is turned for reversing.

3. In a couch bed, a base, a reversible body adapted to be seated on the base with either side uppermost, a double-ended moving fulcrum between the base and the body, pivots carried by the body at its respective ends, a plurality of links connected to each 10 of the pivots and the base, and springs connected between the base and the links so as to tend to raise the body from the base during the movement of the fulcrum in one direction and to oppose the fall of the body 15 to the base during the movement of the fulcrum in the other direction as the body is turned for reversing.

4. In a couch bed, a base, a reversible body adapted to be seated on the base with either 20 side uppermost, a double-ended moving fulcrum between the base and the body, pivots carried by the body at its respective ends, levers pivoted on the base, links connecting the levers with said pivots, and springs 25 connected between the base and the levers so as to tend to raise the body from the base during the sliding movement of the fulcrum in one direction and to oppose the fall of the body to the base during the movement of the fulcrum in the other direction as the body is turned for reversing. 30

5. In a couch bed, a base, a reversible body adapted to be seated on the base with either side uppermost, supporting members carried by the body and having rounded ends to roll and slide on the base, pivots carried by the body at its respective ends, bell crank levers pivoted on the base, links connecting the levers with said pivots, and springs connected between the base and the levers so as to tend to raise the body from the base during the rolling and sliding movement of said rounded ends in one direction and oppose the fall of the body to the base during the rolling and sliding movement of said rounded ends in the other direction as the body is turned for reversing. 35 40 45

6. In a couch bed, a base, a reversible body adapted to be seated on the base with either side uppermost, a double ended fulcrum and pivots carried by the body at its respective ends, a pair of coöperating bell crank levers pivoted on each end of the base, links connecting the levers with said pivots, and springs connected between the base 50 and levers so as to tend to raise the body from the base and oppose its fall to the base as the body is turned on its pivots for reversing. 55

In testimony whereof I affix my signature. 60

JOHN FREEMAN.
